UNITED STATES PATENT OFFICE

166,486

HOURGLASS

Erik Gösta Nyholm, Falun, Sweden

Application June 27, 1950, Serial No. 10,779
In Sweden May 23, 1950

Term of patent 3½ years

(Cl. D42—7)

To all whom it may concern:

Be it known that I, Erik Gösta Nyholm, a subject of the King of Sweden and a resident of Falun, Sweden, whose postoffice address is Hagagatan 20, Falun, Sweden, have invented a new, original, and ornamental Design for an Hourglass, of which the following is a specification, reference being had to the accompanying drawing, forming part thereof.

The figure is a front perspective view of an hourglass, showing my new design.

I claim:

The ornamental design for an hourglass as shown.

ERIK GÖSTA NYHOLM.
